UNITED STATES PATENT OFFICE

147,492

DESIGN FOR A BOX

Freda Diamond, New York, N. Y., assignor to Syracuse Ornamental Co. Inc., Syracuse, N. Y., a corporation of New York

Application March 23, 1946, Serial No. 127,874

Term of patent 7 years

(Cl. D58—11)

To all whom it may concern:

Be it known that I, Freda Diamond, a citizen of the United States, residing in New York, in the county of New York and State of New York, have invented a new, original, and ornamental Design for a Box, of which the following is a specification, reference being had to the accompanying drawing, forming a part thereof.

Fig. 1 is a top view of the box, showing my new design; and

Fig. 2 is a side view thereof with cover removed.

I claim:

The ornamental design for a box, substantially as shown.

FREDA DIAMOND.
